UNITED STATES PATENT OFFICE

154,749

DESIGN FOR A PRESSURE COOKER

Francesco Collura, New York, N. Y., and John N. Polivka, Minneapolis, Minn., assignors to General Mills, Inc., a corporation of Delaware

Application June 5, 1947, Serial No. 139,479

Term of patent 14 years

(Cl. D44—1)

To all whom it may concern:

Be it known that we, Francesco Collura, a citizen of the United States, residing at New York, in the county of New York and State of New York, and John N. Polivka, a citizen of the United States, residing at Minneapolis, in the county of Hennepin and State of Minnesota, have invented a new, original, and ornamental Design for Pressure Cooker, of which the following is a specification, reference being had to the accompanying drawing, forming part thereof.

In the drawing:

Figure 1 is a perspective view of a pressure cooker showing our new design;

Fig. 2 is a top plan of the cooker shown in Fig. 1; and

Fig. 3 is a side elevation of the device of Fig. 1.

We claim:

The ornamental design for a pressure cooker, as shown.

FRANCESCO COLLURA.
JOHN N. POLIVKA.
